WEATHER STRIP AND METHOD OF MAKING
THE SAME

David H. Harnly, Chicago, Ill.; Willard R. Matheny administrator of said David H. Harnly, deceased

Application August 30, 1937, Serial No. 161,593

4 Claims. (Cl. 20—69)

This invention relates to a weather strip and a method of making the same.

It is an object of this invention to provide a deflectable weather strip that is adapted for use in connection with swinging windows, doors or closure members that have a relatively narrow width.

It is a further object of this invention to provide a weather strip in which the free contact or sealing portion will be held more rigidly at an angle and at a greater angle, and occupy less space than is possible in the construction disclosed in my pending application, Serial No. 127,006, filed February 23, 1937.

In accordance with this invention, I use sponge rubber weather strips with backings of fabric or the like vulcanized upon the side faces that produce excellent resiliency for deflecting purposes. I then bevel or cut on a bias the lower rear margin of the weather strip and support such weather strip upon such bevel or slope in connection with a supporting member, so that the free contact or sealing portion will extend at an angle to such supporting member. I then apply a clamp upon the top of the rear margin of the weather strip, directly over the beveled portion, and tightly screw or bolt the clamp down and compress the beveled portion so that the clamp assumes a substantially parallel relation with the supporting member. By thuswise applying the clamp, there will be a strong oblique tension produced in the strip that will cause the free sealing portion or flap to assume a greater angle with the supporting member than the one produced by the bevel.

The invention comprises the novel structure and combination of parts hereinafter described and more particularly pointed out and defined in the appended claims.

In the accompanying drawing which illustrates a preferred form of this invention, and in which similar reference numerals refer to similar features in the different views:

Figure 1 is an elevational view of a swinging or hinged window or closure member equipped with a weather proofing structure involving this invention.

Figure 2 is an enlarged broken sectional view taken upon the line II—II of Figure 1, looking in the direction of the arrows.

Figure 3 is an enlarged broken sectional view taken upon the line III—III of Figure 1, looking in the direction of the arrows.

Figure 4 is a fragmentary perspective view of

a weather strip supported upon its beveled edge before the clamp is applied.

Figure 5 is a view similar to Figure 4 with the clamping strip applied.

In connection with this invention, there is illustrated in the drawing a window frame 1 in which a window 2 is hinged as by hinges 2a. The weather strips involving this invention are adapted to be attached to the side sash members 3 of the window and upon the top and bottom 10 sash members 4. It is obvious that the weather strips may be equally well applied upon the corresponding members of the door frame 1.

The weather strips, which are preferably cut to suitable lengths in accordance with the length 15 and width of the window, consist of substantially flat sponge rubber strips 5 with a fabric backing 6 or other suitable material vulcanized upon the side faces thereof to impart more resiliency thereto. The lower or under rear margin of 20 each strip is beveled to form an oblique base or supporting surface 7, which is free of fabric backing. While this bevel 7 is shown as a straight flat cut, it may be variously formed so as to give an initial slope to the free sealing portion when 25 the strip is in position to be secured in place.

In Figure 4, there is shown a weather strip 6 supported upon its bevel 7 and positioned against a sash portion 3 of the window. It will be noted that by thuswise positioning the weather strip 30 upon its bevel, the free contact or sealing portion initially extends at an angle to such sash member.

While the weather strip is supported upon its beveled portion, a rigid, flat clamping member 8, 35 which is preferably formed of metal, is superposed over the longitudinal rear margin of the strip directly over the beveled portion 7. This clamping strip should be of suitable width in accordance with the width of the beveled portion 40 7, so that it will compress the beveled portion for the greater part of its width, as shown in Figure 5. When the clamping strip 8 has been properly superposed upon the weather strip 5, it is tightly clamped down by means of screws 9 extending 45 through the clamping strip, the weather strip, and into the window sash 3.

The strips 8 are thus clamped down to assume a substantially parallel relation with the sash member 3, as shown in Figure 5. As the clamping strip 8 is clamped down, the forward part of the beveled portion, owing to its greater thickness, will be compressed a great deal more than the rear part. The tension under which the upper fabric 6 is placed by this clamping operation 55

causes the free sealing portion to assume a greater angle than the initial angle caused by supporting the weather strip upon its bevel, as is evident from a comparison of Figures 4 and 5.

5 The weather strips are similarly attached to the sides and upper and lower sash members of the window, so that when the window is in closed position the sealing portions of the weather strips will be deflected, instead of compressed.

10 It will be appreciated that as the sealing portion of a weather strip is deflected to a point where it assumes its initial angle shown in Figure 4, it will offer a slightly greater resistance and thus cause a better sealing relation with the adjacent sash member of the window.

15 I am aware that many changes may be made and numerous details of construction may be varied through a wide range without departing from the principles of this invention, and I, therefore, do not purpose limiting the patent granted hereon otherwise than is necessitated by the prior art.

I claim as my invention:

1. In a weather proofing structure, a resilient 25 and flat weather strip having its lower rear margin beveled for forming a beveled surface thereon, a base member, said weather strip being supported with its beveled surface against said base member and the free portion extending at an angle to the base member, a top clamping member 30 extending longitudinally along the rear top margin of said strip and over said beveled portion, and means for clamping said top clamping member against said beveled portion and bringing said top clamping member into substantial 35 parallel relation with said base member for compressing said bevelled portion and causing the free sealing portion to assume a greater angle than the first mentioned angle.

40 2. In a weather proofing structure, a resilient

flat weather strip having its lower rear margin beveled, clamping means for said rear beveled margin comprising a base member, said weather strip having its beveled surface positioned against said base member and a top clamping member 5 extending longitudinally over the top of the rear margin and over said beveled portion of said weather strip, and means for tightly clamping said top clamping member against said beveled portion for compressing the same and causing 10 oblique tension thereon for causing the free sealing portion to be elevated at an angle from its initial position.

3. In a weather proofing structure, a flat strip of sponge rubber having fabric backing upon its 15 side faces and a rear beveled margin forming a beveled surface, clamping means for said beveled margin comprising a base portion and a top portion, said strip being clamped between said base portion and top portion with its beveled surface in 20 contact with said base portion, said beveled portion being compressed by said clamping means to bring said clamping portions into a substantial parallel relation and causing the free sealing portion of said strip to move and be maintained 25 at a greater angle with respect to said base portion than the angle caused by said beveled surface.

4. In a weather proofing structure, a resilient 30 flat strip having its lower rear margin cut on a bevel, clamping means therefor comprising a base portion and a top portion, said strip having its bevelled portion positioned against said base portion and between said base and top portions and means clamping said top portion upon said base 35 portion into substantial parallel relation and compressing said bevelled portion and causing the free portion of said strip to assume a greater angle than that caused by the bevelled portion.
